DESIGN FOR A COMBINED DUCK AND RABBIT TOY

Harry A. Elder, Chicago, Ill.

Application November 29, 1939, Serial No. 88,550

Term of patent 14 years

To all whom it may concern:

Be it known that I, Harry A. Elder, a citizen of the United States, residing at Chicago, in the county of Cook and State of Illinois, have invented a new, original, and ornamental Design for a Combined Duck and Rabbit Toy, of which the following is a specification, reference being had to the accompanying drawing, forming part thereof.

Figure 1 is a side elevational view of a combined duck and rabbit toy; and

Figure 2 is a reverse side elevational view thereof, showing my new design.

The article is made of flat material and is of no appreciable thickness.

I claim:

The ornamental design for a combined duck and rabbit toy, as shown and described.

HARRY A. ELDER.
